CLAIM

The ornamental design for a foldable charging stand as shown and described.

DESCRIPTION

FIG. 1 is a top, front, and left side perspective view of a foldable charging stand showing our new design in a first position;

FIG. 2 is a bottom, rear, and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a rear elevational view thereof shown in a second position;

FIG. 10 is a top plan view thereof;

FIG. 11 is a right side elevational view thereof;

FIG. 12 is a left side elevational view thereof;

FIG. 13 is a top, front, and left side perspective view thereof shown in a third position;

FIG. 14 is bottom, rear, and right side perspective view thereof;

FIG. 15 is a left side elevational view thereof;

FIG. 16 is a top, front, and left side perspective view shown in a fourth position and in an environment of use;

FIG. 17 is a top, rear, and left side perspective view thereof;

FIG. 18 is a top, rear, and right side perspective view thereof;

FIG. 19 is a top, rear, and right side perspective view thereof shown in an environment of use;

FIG. 20 is a top, front and left side perspective view thereof shown in a fifth position with added broken lines to designate positioning of an optional throughway; and,

FIG. 21 is a front elevational view thereof.

(Continued)

The broken lines in the figures represent portions of the foldable charging stand and environments of use that form no part of the claimed design.
